UNITED STATES PATENT OFFICE.

SAUNDERS NORVELL, OF NEW YORK, N. Y., ASSIGNOR TO THE FIRM OF MCKESSON & ROBBINS, OF NEW YORK, N. Y.

DESIGN FOR A BOTTLE.

48,757.

Specification for Design.

Patented Mar. 21, 1916.

Application filed November 23, 1915. Serial No. 63,127. Term of patent 14 years.

To all whom it may concern:

Be it known that I, SAUNDERS NORVELL, a citizen of the United States of America, residing at New York, in the county of New York and State of New York, have invented a new, original, and ornamental Design for Bottles, of which the following is a specification, reference being had to the accompanying drawing, forming part hereof.

The figure is a perspective view of a bottle embodying my design.

I claim:

The ornamental design for a bottle, as shown.

SAUNDERS NORVELL.
